UNITED STATES PATENT OFFICE.

WILLIAM LOGAN LEACH, OF BROWNWOOD, TEXAS.

DETACHABLE FASTENER FOR CYLINDRICAL SCREENS.

1,347,341.

Specification of Letters Patent.

Patented July 20, 1920.

Application filed April 10, 1917. Serial No. 160,983.

To all whom it may concern:

Be it known that I, WILLIAM L. LEACH, a citizen of the United States, and a resident of Brownwood, in the county of Brown and State of Texas, have invented a certain new and useful Improvement in Detachable Fasteners for Cylindrical Screens, of which the following is a specification.

My present invention relates generally to 10 seeding devices, and more particularly to certain improvements therein upon the apparatus designed for the same use as described and claimed in my Patent 1,124,036, dated January 5, 1915, my object being to 15 generally improve the efficiency and effectiveness of my patented arrangement by the provision of improved means to detachably connect and fasten the ends of a strip of reticulate material in order to form the 20 grading cylinder which, owing to these features may be readily renewed from time to time as becomes desirable or necessary.

Figure 1 is a partial vertical section taken longitudinally through one end of the grading cylinder;

Figs. 2 and 3 are respectively a perspective view of, and a sectional view through, a portion of the grading cylinder, and

Fig. 4 is a detail perspective view of one 30 of the eccentric clamps.

Referring now to these figures, and particularly to Fig. 1, the grading cylinder indicated generally at 10 is, as usual, formed of a framework of which the inner longitudinal seed agitating baffle strips 11 form a part, the cylinder having a reticulated wall consisting of successive sections 11^a of different mesh, gradually of an increasing gage from one end to the other, the cylinder 40 being secured upon and rotatable with an axial shaft 12 and being mounted therewith in longitudinally inclined position, with its section of greatest gage at the lower end, the shaft 12 being journaled in bearings 13 45 carried by a framework, including upper and lower side beams 14 and 15 and corner uprights 16.

The several sections 11^a of the grading

cylinder, which may be formed of either perforated metal or screen wire, each consist 50 of a strip of some such suitable material extended circumferentially of the cylinder and secured in detachable relation therearound by clamps consisting of hooks, bolts 11^b, apertured brackets 11^c, and eccentrics 11^d, all as 55 shown in Figs. 2, 3 and 4. Each reticulated strip has sheet metal relatively engaging end pieces 11^e to which the brackets 11^c and the bearing pieces 11^f of the eccentric 11^d are secured, so that with the hook bolts 11^b 60 adjusted through the brackets 11^c and engaged with the eccentric, the latter upon turning movement serves to draw the sheet metal ends 11^e firmly together in clamping relation. This movement of the eccentric 65 11^d to either operative or inoperative position may be effected by a suitable tool or implement extended into its socket 11^g as seen in dotted lines in Fig. 2.

It is thus obvious that the several sections of the grading cylinder may thus be interchanged and renewed, without difficulty, rendering the cylinder adaptable to various uses, that is various materials, by inserting screen mesh for instance of different gages.

I claim:

In an apparatus of the character described, a clamping connection for relatively movable parts including a bracket carried 80 by one of said parts, a pair of laterally spaced bearing members carried by the other of said parts, a shaft having its ends journaled in the said bearing members and having an eccentric portion and a tool receiving socket between the bearing members, and a bolt one end of which is loosely adjustably mounted through the bracket and the opposite end of which has a hook detachably engaging the eccentric portion of 90 the said shaft as and for the purpose set forth.

WILLIAM LOGAN LEACH.
